UNITED STATES PATENT OFFICE.

FREDERIC BARR, OF NEW YORK, N. Y.

FULL-SOCKET SWITCH.

1,079,740.

Specification of Letters Patent.

Patented Nov. 25, 1913.

Application filed July 20, 1911. Serial No. 639,522.

To all whom it may concern:

Be it known that I, FREDERIC BARR, a citizen of the United States, and resident of New York, in the county of Kings and State 5 of New York, have invented certain new and useful Improvements in Pull-Socket Switches, of which the following is a specification.

My invention relates to switches for incandescent lamp sockets and particularly the chain guide construction.

The object is to completely insulate the operating cord or "chain" as it is commonly termed.

15 Another object is to provide a special guide for the chain at the point where it passes through the socket shell which guide is not attached either to the socket or to the shell but may be readily assembled with the 20 socket and shell and readily separated therefrom when desired.

Another object is to prevent relative movement of the socket, the chain guide and the shell.

25 In the preferred form of the invention the switch parts are carried by an insulating block formed in two parts with a channel extending around one side between the parts for the operating chain. The removable 30 chain guide has a bell which extends through the shell and a base or anchor plate which fits between the insulating block and the shell without being attached to either member. The insulating block has a lug projecting into a slot in the shell to prevent relative 35 rotation and the base plate of the chain guide has fingers loosely embracing the lug.

Figure 1, is a sectional view of the casing or shell showing the switch block, operating 40 chain and guide in side elevation. Fig. 2, is a front view of the complete socket showing the parts of the interior dotted. Fig. 3, is a plan view, the cap of the shell being removed. Fig. 4, is a plan and sectional view 45 on the plane of the line X, X of Fig. 1. Fig. 5, is a rear perspective view of the chain guide. Fig. 6, is a fragmentary side view provided with lugs for securing it to the shell. Fig. 7, is a rear view of the chain 50 guide construction of Fig. 6. Fig. 8, is a front view of a socket with another modification of the chain guide. Fig. 9, is a rear view of the chain guide of Fig. 8 enlarged. Fig. 10, is a sectional view of the same on 55 the plane of the line Y, Y of Fig. 9.

The insulating block for carrying the stationary switch contact or contacts as the case may be (not shown) is formed in two parts 1 and 2. The upper part 1 has a flange 3 which extends around one side and the parts 60 are secured together by means of screws 4 and 5 which pass through the flange 3.

Circuit terminals 6 and 7 are connected to the screws 4 and 5 in recesses in the upper porcelain 1. I use the term "porcelain" 65 herein as a generic term covering the porcelain or equivalent insulating material.

The lamp terminals 8 and 9 are suitably secured to the lower porcelain 2 and may be 70 of any suitable shape and arrangement.

A rotating switch member of any suitable type (not shown) is carried by the rotatable insulating disk 10 which is mounted on the spindle 11. This disk 10 substantially fills the recess formed by the flange 3 and the 75 upper and lower porcelain members.

The shapes of the upper and lower porcelain members, the flange 3 and the disk 10 are such as to leave a curved channel 12 whose upper and lower walls are formed respectively by the upper and lower porcelain. Its inner wall is formed by the periphery of the insulating disk 10 and the end walls are formed by the shoulders 13 and 14 of the 80 flange 3.

A lever 15 having ratchet teeth 16 to operate with the insulating disk 10 which carries the rotating switch member is mounted to oscillate about the axis of the spindle 11. A spring 17 tends to hold the operating 90 lever 15 in the position shown in Fig. 4 where it presses against the shoulder 15. The operating cord or chain 18 has one end secured to the lever 15 and the lever and chain operate in the curved channel 12 previously described. When the chain 18 is pulled the lever 15 is oscillated so as to rotate the insulating switch carrier 10 until the lever 15 strikes the insulating shoulder 14. When the pull on the chain is released 100 the spring 17 returns the lever and chain to the positions shown in Figs. 1 and 4.

The parts thus far described are inclosed in a shell or casing consisting of the body 19 and the cap 20 which are detachably connected together in any suitable manner, the flange 21 fitting over the upper end of the body 19. Insulating material for instance, fiber 22 and 23 is provided preferably in the shell to insulate it from the interior mech- 110

anism. This forms the outer wall of the channel 12.

To guide the chain 18 at the point where it passes through the shell I provide a bell 5 or tubular member 24 which has a base or anchor plate 25 secured thereto in a suitable manner as for instance, by upsetting or flanging the inner end as at 26 in Fig. 5. To facilitate assembling, the shell body 19 is 10 provided with a slot 27 in its upper edge to accommodate the guide tube 24. The upper end of this slot is covered by the flange 21 when the parts of the shell are assembled. The base plate 25 is preferably curved so as 15 to correspond with the shape of the outer walls of the cylindrical insulating members 1 and 2 and the inner wall of the fiber 22 inside the shell body 19. This plate 25 is preferably made of sufficient size to bridge the 20 channel 12 between the upper and lower flanges of the porcelain switch carrying block as shown in Fig. 1. When the parts are assembled as shown in Figs. 1, 2, 3 and 4 the chain guide is held rigidly by reason of 25 the respective shapes and arrangements of the parts and without the necessity of securing the chain guide either to the switch carrying block or socket or to the inclosing casing or shell.

30 To prevent relative rotation of the switch carrying block and the shell I provide a lug 28 which projects from the upper porcelain 1 into the upper end of the slot 27 in the body of the shell. The operation of the 35 switch and the screwing in of the lamp (not shown) will therefor not disturb the relative positions of the parts. The chain guide base plate 25 is preferably cut away at 29 to allow for the lug 28 and provide fingers 30 and 31 to embrace the lug. The parts 40 are thus held securely against relative displacement without the expense of providing means for securing the chain guide either to the insulating block or the shell. This also 45 reduces greatly the cost of assembling the parts. When the cap 20 is removed from the body 19 of the shell, the switch mechanism and chain guide can be readily removed from the body of the shell. The button or knob 32 on the end of the chain 18 50 will then prevent the chain guide from falling off. If it is desired to test the switch when out of the casing the chain guide can be readily positioned against the outer wall 55 of the insulating block and held there by the finger or thumb while the chain is operated.

In the modification shown in Figs. 6 and 7 the base plate 35 of the chain guide has 60 lugs 36 and 37 bent outwardly so as to fit on the outside of the shell 38 while the base plate fits on the inside. This connects the chain guide to the shell as distinctive from simply locating the chain guide base in the 65 space between the insulating block and the

insulating fiber lining of the shell as previously described. In this construction however, the base plate is also reinforced by the presence of the insulating block so that the metal of which the base plate is formed can 70 be quite thin.

In the modification shown in Figs. 8, 9 and 10 the bell portion 40 is turned downwardly and the base plate 41 has two lugs 42 and 43 which fit inside of the shell 44 and two lugs 45 and 46 which fit outside of the shell. The metal of the base plate being very thin, the upper lug 45 may fit under the flange 47 of the cap as shown in Fig. 8. In this way the flange of the 80 cap reinforces the base plate.

The right to claim the specific constructions shown in Figs. 6 to 10 inclusive, is reserved for other applications.

The subject matter of Figs. 1 to 5 inclusive has been divided out of my application #608,656 filed February 15th, 1911 and this application is a continuation of the former to that extent.

What I claim is:—

1. In a pull socket, an insulating block formed of two parts with a channel around one side, an insulating carrier rotatably mounted between the upper and lower parts of the block, an operating lever, an operating chain connected to said operating lever and operating in said channel, a shell inclosing the block and lever, and a chain guide extending through said shell and having a base plate removably held in place between said block and said shell without attachment to either said block or said shell. 90

2. In a pull socket, an insulating block having a channel around one side, an operating lever having one end extending into said channel, an operating chain connected to said lever and operating in said channel, a shell inclosing said block and lever, and a chain guide extending through said shell and having a base plate bridging said channel and held removably between said shell and said insulating block, by the relative shape of the parts without attachment to either said block or said shell. 100

3. In a pull socket, an insulating block having a channel around one side, an operating lever having one end extending into said channel, an operating chain connected to said lever and operating in said channel, a shell inclosing said block and lever, and a chain guide extending through said shell and having a curved base plate part of which fits against the outer wall of the insulating block and part of which fits against the shell without attachment to either said block or said shell. 110

4. In a pull socket switch, a block carrying the switch members and having a laterally projecting lug, a shell inclosing said block and switch members consisting of a 120

body having a slot and a cap detachably secured to the body and a chain guide consisting of a plate located between said block and said shell and having fingers positioned by said lug and a bell projecting through said slot.

5. In a pull socket, an insulating block carrying the switch members and having a laterally projecting lug, a shell formed in 10 two parts inclosing said insulating block and switch members, one of the parts of said shell having a slot in one edge into which said lug projects and a chain guide consisting of a plate fitting between the insulating 15 block and the shell and a bell projecting through said slot, the relative shape and location of the insulating block, the shell, the plate and the bell being such that the chain guide is held in place without attachment 20 to the shell or the block when the parts are assembled.

6. In a pull socket switch, a block carrying the switch members and having a laterally projecting lug, a shell inclosing said 25 block and switch members consisting of a body having a slot into which said lug projects and a cap detachably secured to the body and a chain guide consisting of a plate located between said block and said shell 30 and having fingers positioned by said lug and a bell projecting through said slot.

7. In a pull socket switch, an insulating block having a lug, an inclosing shell having a slot into which said lug projects, a 35 chain guide bell projecting through said slot and an anchor plate secured to the bell inside the shell.

8. In a pull socket switch, a shell formed in two parts, a body and a cap detachably 40 secured together, said body having a slot extending below the edge of the cap when the parts are assembled, a cylindrical insulating block substantially fitting said shell and carrying the switch parts, a chain guide 45 consisting of a bell projecting through said slot in said shell and a curved anchor plate secured to said bell and fitting snugly in the shell between the cylindrical insulating block and the shell but independent of the 50 block when the shell is removed and means for preventing relative rotation of said bell and block.

9. In a pull socket, a switch carrying block, a shell inclosing said block and a chain guide having a base plate removably held between said block and said shell and means independent of said chain guide for preventing said block from rotating inside of said shell.

10. In a pull socket, a switch carrying 60 block, a shell inclosing said block and a chain guide having a base plate removably held between said block and said shell and a lug projecting from said block into an engagement with said shell to prevent its rotation.

11. In a pull socket, a switch carrying block, a shell inclosing said block, a chain guide having a base plate removably held between said block and said shell and a lug 70 projecting from said block through said plate.

12. In a pull socket, a shell body having a slot, a removable chain guide having a bell extending through said slot and a base plate 75 conforming to the shape of the inside of said shell body adjacent said slot, and a switch block in said shell body shaped to hold said base plate in position but removable from said shell body independently of said 80 chain guide.

13. In a pull socket, a shell body having a slot, a removable chain guide having a bell extending through said slot and a base plate 85 conforming to the shape of the inside of said shell body adjacent said slot, and a switch block in said shell body shaped to hold said base plate in position but removable from said shell body independently of said 90 chain guide and having a lug to prevent rotation of said block in said shell.

14. In a pull socket, a shell formed in two parts, one of said parts having a slot, a switch-carrying block inclosed by said shell, and a chain guide consisting of a base plate 95 fitting and held in place between said switch block and said shell and a bell projecting from said base plate through said slot, said switch block being removable from said shell independently of said chain guide.
